TRACTOR

Afton B. Root, Detroit, Mich., assignor to Massey-Ferguson Inc., Detroit, Mich.

Filed Feb. 14, 1972, Ser. No. 226,366

Term of patent 14 years

Int. Cl. D12—09

U.S. Cl. D40—5

Fig. 1

Fig. 2

Fig. 3

Fig. 4

Fig. 5

FIG. 1 is a perspective view of a tractor embodying the new design and taken generally from the left rear thereof;

FIG. 2 is a rear elevational view of the tractor;

FIG. 3 is a perspective view of the tractor taken from the right rear thereof;

FIG. 4 is a front elevational view of the tractor; and

FIG. 5 is a top plan view of the tractor, with the steering wheel and seat being omitted for ease of illustration.

I claim:

The ornamental design for a tractor, substantially as shown.
